UNITED STATES PATENT OFFICE

2,676,438

FLOOR SANDER

Bailey P. Brien, Chattanooga, Tenn.

Application October 25, 1950, Serial No. 192,069

2 Claims. (Cl. 51—176)

1

My invention relates to surfacing and leveling machines and more particularly to an arrangement for enabling the conventional drum sanding machine to be used in the uniform surfacing of wooden objects and other structures such as bowling alleys and the like.

The use of the well known drum sander for surfacing floors and bowling alleys is very common. However, certain problems have arisen, particularly in connection with its use on bowling alleys. These problems primarily result from the fact that no provision is made on the machine for guiding the operator in his attempts to make such a cut across the alley as will produce a uniform surface. Non-uniformity of the surface of the alley which the operator cannot accurately detect when using the machine to make the cut, movement of the sander across the surface at a non-uniform speed, causing it to make cuts which are deeper at some places than at others, and differences in the hardness of the wood used in different parts of the alley frequently result in an uneven surface.

Some of these problems have been recognized in the prior art and attempts have been made to overcome or obviate the defects in the equipment and mode of operation. Generally these attempts have been directed towards mounting the drum in a built-up frame or carriage which rides in a horizontal plane on sets of tracks positioned at right angles to each other. Complicated and bulky structures of this type require a great deal of time to set up and remove and are slow in operation. See patent to Martin, 1,308,762. Other types use a drum sander with a drum sufficiently wide to substantially span the width of the bowling alley. Track is set in the gutters and the drum carrying frame is mounted to ride on the track. See patent to Muzzo, 2,206,671 and patent to Kirchner, 2,290,596. It is, of course, not possible to adapt the conventional drum sander to this arrangement without extensive alterations which prevent its use in the usual manner and for other purposes.

Applicant with a knowledge of all of these problems in the prior art has for an object of his invention the provision of an arrangement employing the conventional drum sander for uniformly finishing a surface.

Applicant has as another object of his invention the provision of a system for adapting a conventional drum sander to the uniform resurfacing of bowling alleys without material alteration.

Applicant has as another object of his inven-

tion the provision of a drum sander which is adapted to ride directly on the surface to be re-finished and so arranged as to only remove the surface to a predetermined level.

Applicant has as another object of his invention the provision of a conventional drum sander which is adapted to ride directly upon the finished surface with an arrangement for limiting the level or depth of the cut taken.

Applicant has as a further object of his invention the provision of an attachment for a conventional drum sander, adapted to traverse the surface treated and to coast with a stop of uniform height for limiting the cut of the sander and provide a uniform surface.

Other objects and advantages of my invention will appear from the following specifications and accompanying drawings, and the novel features thereof will be particularly pointed out in the annexed claims.

In the drawings, Figure 1 is a perspective view of a conventional drum sanding machine employing my improved attachment and positioned on a bowling alley.

Figure 2 is an end elevation of a bowling alley, partly in section, showing the tracks employed in my improved attachment and the leveling device therefor.

Figure 3 is a cross-section of the cross-member and clamp of my attachment taken along the line 3—3 of Figure 1.

Figure 4 is a detail, partly in section, of my improved rail mounting shoe.

Figure 5 is a detail showing the connection between the cross member and a vertical arm, and

Figure 6 is a sectional view taken along the line 6—6 of Figure 5.

Referring to the drawings in detail, I designates the frame of a conventional drum sanding machine such as the type CF-12 made by Porter Cable Machine Co., of Sandusky, Ohio. It includes a swinging carriage for raising and lowering the drum 2 with respect to the surface being operated upon in response to force applied

to the lever 3' pivotally mounted on handle 3. The usual power motor 4 is provided to rotate drum 2 through pulleys 5, 6 and belt 7. Mounted on the upper front portion of the swinging carriage is a channel shaped member 8 for reception of a cross-member 9 which extends transversely of the carriage and spans or bridges the two gutters 10, 11 of a bowling alley. The structural relation of the parts connecting the channel shaped member 8 and the cross-member 9 is described more in detail hereinafter. Mounted

on the ends of the cross-member 9 are a pair of vertical arms 12 and 13. The lower ends of these arms are bifurcated or forked to receive rollers 14, 15 carried by shafts 16, 17 which bridge the prongs of the forks. The rollers 14, 15 are adapted to cooperate with rails 18, 19 for limiting the cut of the machine in traversing the surface of the alley 20.

The rails 18, 19 extend the length of the alley and are supported in the gutters 10, 11 by a series of spaced shoes positioned at intervals along each gutter. Each shoe, designated generally 21, includes a base 34 with a substantially flat intermediate portion and upturned edges. The central portion is provided with a thickened wall having a screw-threaded bore 22 for the reception of the screw-threaded bolt 23. The upper end of the bolt 23 is also screw-threaded and is seated in a socket in the expandable clamp 24. A nut 25 on the upper end of the bolt serves to abut the lower face of clamp 24 and is adjustable to raise or lower the clamp into proper position. The clamp 24 has an upper bifurcated portion which provides the jaws for the clamp and is adapted to receive a rail of substantially circular cross section. The clamp is contracted about the rail by a bolt 27 which bridges the jaws 28, 29. Studs 30, 31 pass through threaded bores in the upturned ends of base 34 and adjustably engage the curved walls of the gutters 10 and 11 for leveling the track 18, 19. Nuts 32, 33 threaded on the studs 30, 31 engage the inner face of the base 34 and tend to lock the studs 30, 31 in adjusted position.

Arms 12 and 13 are raised and lowered by an adjustable mechanism such as shown in detail in Figures 5 and 6, wherein the upper extremity of arm 12 is formed into a channel shaped socket. Formed in the front wall of the socket is an elongated slot 35 adapted to loosely receive the body of a stud 36 which passes therethrough and through an opening in saddle 37, said stud having cross-threaded engagement with an opening in cross-member 9 which is seated in a recess 37' formed in the saddle 37. The stud 36 carries a washer 38 which bears against the outer face of the front wall of the channeled socket of arm 12 to lock the arm in adjusted position with respect to the cross-member 9 when the stud 36 is tightened.

The saddle 37 is slidable in the channel shaped socket of the arm 12 or 13 and at the upper end of each arm is an apertured boss 39 in vertical alignment with the saddle. A screw-threaded bolt 40 is mounted in the apertured boss 39 with its lower end in bearing contact with the upper surface of the saddle 37 and a bevel gear 41 is threadedly mounted on the upper end of the bolt 40 which meshes with a bevel gear 42 affixed on an end of a shaft 43. The shaft 43 extends longitudinally of the cross bar 9 in superposed relation thereto and is journaled in bearing brackets 43' attached to arms 12 and 13. A crank or other suitable means may be employed for turning shaft 43 which through the bevel gears 41 and 42 rotate the bolts 40 to adjust the saddles 37 in the arms 12 and 13.

For the purpose of adjusting and supporting the cross-member 9 with respect to the sanding machine, the channel shaped member 8 is mounted on the carriage of the sanding machine through bracket 44 by bolts or other conventional means. A series of studs 45, 45, 45, 45 pass through the flanges of channel shaped member 8 and engage the upper and lower edges of the cross member 9. A retainer block 46 is mounted

vertically across the channel in member 8 by screws 47 or other conventional means. The block 46 also carries a clamping screw 48 which cooperates with studs 45, locked in place by locking nuts 49, for maintaining the cross-member 9 in adjusted position.

In use, the tracks 18 and 19 must first be placed in the proper elevation with respect to each other. This is accomplished in the manner and by the use of the tools disclosed in Figure 2 at 50. This tool is preferably comprised of a thin sheet of fiberboard, plywood, or lumber cut to the configuration indicated in the figure so that the lower edge 51 of the intermediate portion of the tool rests upon the surface of the alley and the lower edges 52, 52 of the reduced extremities of the tool rest upon the track rails 18, 19 when they are in proper adjustment. This adjustment is accomplished by raising and lowering the track through the studs 30, 31, bolt 23, and clamp 24. In carrying out this operation the tool 50 is moved up and down the alley and the track may be leveled at intervals from a few inches to a few feet.

When the above procedure is completed, the arms 12, 13 are then adjusted with respect to cross-member 9 to the depth of cut desired. Then clamping screw 48 and studs 45, 45 may be loosened and the sanding machine set at any desired position with respect to the two arms 12, 13 by simply sliding the cross-member 9 with respect to channel member 8. Thereafter, the clamping screw 48 and studs 45, 45 may be tightened to maintain the relation. However, as each cut is taken along the alley, a new adjustment of the arms 12, 13 and cross-member with respect to the channel member 8 and sanding machine must be made to enable the entire surface of the alley to be progressively covered by the machine, while keeping the arms and their rollers 14, 15 in registration with the track 18, 19.

In operating the machine after the above adjustments have been made, the operator through the usual switch energizes the motor 4 and starts the drum 2 rotating. He then actuates lever 3' to lower the drum into engagement with the surface to be acted on and through the use of the handle 3 he moves the machine over the floor removing such surface. However, the depth of the cut taken by the drum is not determined by such factors as differences in the hardness of the materials of the floor, the speed at which it traverses the surface, or even by the balance of force supplied to the handles. It is determined solely by the adjustment of the track 18, 19, the arms 12, 13 and the cross member 9. When the predetermined depth of cut has been reached or accomplished, the rollers 14, 15 carried by arms 12, 13 move along the track 18, 19, as the machine is moved along the alley. This limits the downward movement of the carriage and in turn the downward movement of the drum 2 carried by it and insures an even precision cut for the entire surface of the alley. In this connection it will be understood that there may be instances where portions of the alley have worn more than others. These worn portions may be at the predetermined depth. In that event the sander will only remove the surface from the raised portions of the alley and bring them all to the same level.

While the present description sets forth a preferred embodiment of the invention, changes may be made in the construction without departing from the spirit of the invention and it is therefore desired that the present embodiment be con-

sidered in all respects as illustrative and not restrictive, reference being had to the appended claims rather than to the foregoing description to indicate the scope of the invention.

Having thus described my invention, I claim:

1. A sanding machine for bowling alleys comprising a rotatable sanding drum, a movable carriage supporting said drum for vertical movement towards and from the surface of the alley, longitudinal rails along each side of the alley, a channel member mounted on said carriage in a horizontal plane above said drum, a cross member slidably mounted in said channel member with its outer ends disposed above said rails, vertical arms at the outer ends of said cross member having rollers at their lower ends adapted to movably contact said rails, the upper ends of said arms each having a vertical channel with an apertured boss at the top, saddles slidably mounted in the channels of said arms connected to the outer ends of said cross member, screws mounted in the bosses of said channels having their lower ends in bearing contact with said saddles, bevel gears threaded on the upper ends of said screws, a rotatable shaft mounted above and extending parallel to said cross member having bevel gears at each end in mesh with the bevel gears of said screws for simultaneously raising and lowering said screws to vertically adjust said arms and means for locking said arms in adjusted position.

2. A sanding machine for bowling alleys comprising a rotatable sanding drum, a movable carriage supporting said drum for vertical movement towards and from the surface of the alley, longitudinal rails along each side of the alley, supports for said rails, each support including a base plate having upturned ends adapted to be positioned transversely of a gutter of said alley, screw studs mounted in the upturned ends of said base plate for adjusting the level of the base plate,

a bolt mounted vertically in the center of said base plate, a nut adjustable on the upper end of said bolt, an expandable clamp on the upper end of said bolt seated on said nut, said clamp having jaws on its upper end to receive and support said rails, a cross member slidably mounted on said carriage above said drum extending transversely of the alley with its outer ends disposed above said rails, vertical arms at the outer ends of said cross member having rollers at their lower ends adapted to movably contact said rails, means slidably connecting said arms to the outer ends of said cross member for vertical movement, screw studs mounted in the upper ends of said arms adjustable to raise and lower said arms with respect to said cross member, bevel gears on the upper ends of said last mentioned studs, a rotatable shaft mounted above and extending longitudinally of said cross member, and bevel gears mounted on the ends of said shaft in mesh with the gears of said studs whereby said studs are simultaneously adjusted upon rotation of said shaft.
